UNITED STATES PATENT OFFICE.

PHILIP W. MOORE, OF EVANSTON, ILLINOIS, ASSIGNOR TO THE P. & M. CO., OF CHICAGO, ILLINOIS, A CORPORATION OF ILLINOIS.

ANTICREEPER.

1,140,345.

Specification of Letters Patent. Patented May 18, 1915.

Application filed August 31, 1914. Serial No. 859,289. Renewed April 3, 1915. Serial No. 18,920.

To all whom it may concern:

Be it known that I, PHILIP W. MOORE, a citizen of the United States, residing at Evanston, in the county of Cook and State 5 of Illinois, have invented new and useful Improvements in Anticreepers, of which the following is a full, clear, concise, and exact description, reference being had to the accompanying drawings, forming a part of 10 this specification.

My invention relates to improvements in anti-creepers for railroad rails of the general type wherein the creeping thrust produces a tendency to tilt the anti-creep 15 about a horizontal axis at right angles to the length of the rail, said tilting action tending to increase the hold of the anti-creep on the rail base.

The objects of my invention are: To provide a rail anchor which maintains an effective hold on the rail base when the forward thrust against the tie is relieved. To provide a rail anchor in which a very firm grip on the rail base may be secured independently of the tilting action. To provide a rail anchor of this type, of generally improved construction and increased efficiency in holding the rail.

I have illustrated in the accompanying 30 drawings a rail anchor which embodies the invention and which has various practical advantages hereinafter pointed out. The invention may, of course, be embodied in different forms.

Figure 1 of the drawings is an elevation of the rail anchor assembled on the rail. Fig. 2 is a top plan view thereof. Fig. 3 is a side elevation thereof. Fig. 4 is a perspective view of the main part or yoke. Fig. 5 is a perspective view of the smaller 40 part or mate.

The usual cross-tie 1 supports the rail 2 in the customary manner. The rail anchor is applied to the rail adjacent to the cross-tie and, in the form illustrated consists of two parts which may be termed for convenience the yoke 3 and the mate 4. The yoke is provided with hooks or jaws 5, 6 at the opposite ends thereof. The jaw 5 is adapted to fit over and bear down on the upper surface of the rail base. The jaw 6 clears the opposite side of said base and receives loosely the mate 4, which latter grips the edge of the rail base. (See particularly 55 Figs. 1 and 2 of the drawings.) The trans-

verse element or cross bar 7, which connects the jaws 5 and 6 is not arranged in the same vertical plane as the latter, but is arranged to the rear thereof as shown in Fig. 2, that is, not as far advanced in the direction in 60 which the rail tends to creep, said direction being indicated by the arrow. A pair of downwardly extending flanges 8, 9 is provided to bear against the vertical face of the cross-tie. The general relation of the 65 parts is such that when the rail tends to creep, the yoke tends to tilt, whereby the cross bar 7 bears upwardly against the bottom of the rail and the portions of the jaws which overlie the rail base bear downwardly 70 toward the top thereof to increase the frictional grip thereon of the parts of the anchor in direct contact therewith. (See Fig. 3).

An auxiliary jaw 10 is provided at one 75 end of the cross bar 7, adapted to grip the edge of the rail base at a point nearly in line with said cross bar. The rail is, therefore, engaged by two jaws on this side, one of which engages only the top surface of 80 the base and the other which engages it both above and below. The mate 4 is arranged about opposite the space between said two jaws and is provided with a double jaw 11 for gripping the opposite side of 85 said rail base. The jaw 11 is, in effect, a single jaw having a central part cut away, as shown at 12, thereby providing a locking recess hereinafter referred to. Said mate has also a downwardly extending rib 90 13 which is somewhat under-cut to match a correspondingly under-cut wall 14 on the end of the cross bar 7 opposite the jaw 10. The engaging surfaces just mentioned are not only inclined from a vertical plane to 95 provide for an interlocking thereof, but they are also arranged somewhat diagonally with respect to the length of the rail, whereby as the mate is caused to slide along the wall 14 it is crowded inwardly toward the rail 100 so as to cause the jaws 5, 10 and 11 to grip the rail base firmly between them. A flexible extension or tongue 15 projects rearwardly from the jaw 6 and may be bent down into the recess 12 of the mate to lock 105 the same against a rearward movement after the rail base has been firmly gripped by the jaws in the manner just described.

In applying the device to the rail, the yoke is first put in place by hand, said yoke 110

being sufficiently cut away beneath the jaws 5 and 6 to permit it to be readily positioned. The mate 13 is then fitted in place and driven toward the tie with a heavy hammer or maul as far as it can be driven, the flanges 8, 9 being so positioned with respect to the tie, that they bear firmly against the latter when the parts are in final position, as shown in Fig. 3. Not only is the rail gripped between the jaws 10 and 11, but the jaw 5 also fits over the side and top of the rail base and as the mate is being driven toward the tie, the tendency is for the rail anchor to tilt about a horizontal axis transverse to the length of the rail and located possibly about where the cross bar 7 comes in contact with the base of the rail. The jaw 5, therefore, bears down firmly against the top of the rail base, and the jaw 6 bears down firmly against the top of the mate 4 thereby developing considerable friction. As previously stated, the mate is locked against a rearward movement, after having been driven toward the tie as far as possible. When the rail tends to creep in the direction shown by the arrow in Fig. 2, the tendency is for the rail anchor to tilt in the same manner as just described, whereby a powerful gripping action is obtained between the cross bar 7 which exerts an upward thrust on the rail base and the jaws 5, 6 and 11 which exert a downward thrust thereon. The downwardly extending flanges 8 and 9 transmit the creeping thrust to the tie. The intention is to have both flanges bear against the tie, but where the latter happens to be so irregular that only one flange bears against it, the tilting action results nevertheless, the device being effective in either case to prevent creeping.

It is obvious that the desired frictional hold is maintained on the rail base as long as the thrust against the tie continues. Said rail anchor maintains its hold, however, even when said thrust is relaxed. Such relaxation occurs when a rearward movement of the rail takes place due to a reversal of traffic or to a contraction caused by cold and for other causes. Said hold is maintained under these conditions because of the fact that the mate has been driven to and locked in such a position as to draw the jaws on the opposite sides toward each other and furthermore the jaw 10 is located somewhat to the rear of the position of the cross bar 7, so that any tendency of the rail anchor to tilt in the opposite direction from which it normally tends to tilt, is prevented by said jaw as well as by the general tight fit of all of the parts. Such rearward movement sometimes develops considerable stress tending to tilt the anchor, where the ballast is frozen and the flanges 8, 9 embedded therein. For this reason, the provision of the auxiliary jaw 10 is important as it of-

fers a positive obstruction to tilting in such a direction as would tend to relax the grip between the rail anchor and the rail base.

Various changes may be made in the details of construction without departing from the spirit of the invention, as expressed in the appended claims.

Having thus described my invention, what I claim as new and desire to secure by Letters Patent of the United States is:

1. An anti-creeper comprising a yoke arranged to engage a rail base above and below the same and having a tie engaging flange beneath the rail, the parts being so disposed as to cause a tendency of said anti-creeper to tilt about a transverse horizontal axis when the rail tends to creep, to increase the grip of the anti-creeper on said rail base and means for preventing tilting in a reverse direction.

2. An anti-creeper comprising a yoke having a wedging member received within one of its jaws and adapted to grip the rail base between itself and the opposite jaw, a tie engaging flange beneath said rail base, and an auxiliary jaw to engage the top of the rail base to the rear of the before mentioned rail engaging parts.

3. An anti-creeper comprising a yoke having a hook at each end, one of which is larger than the other, a wedging element received within said larger hook and arranged to grip the rail base, the smaller hook engaging the opposite side of the rail base at the side and top thereof and an auxiliary jaw also arranged to engage said rail base and located to the rear of said smaller hook.

4. An anti-creeper comprising a yoke and a mate, said yoke consisting of a cross bar having a pair of jaws integrally connected with one end thereof and arranged one in advance and one to the rear of said cross bar, the latter having also a jaw at its opposite end which clears the rail base, said member being received loosely within said jaw and diagonally arranged under-cut walls associated with said larger jaw and said mate, which engage each other to cause an inward movement of said mate when thrust toward said larger jaw.

5. An anti-creeper comprising a yoke and a mate, a small jaw at one end of said yoke arranged to engage the rail base directly and a large jaw at the other end thereof arranged to partially inclose said mate, said yoke and said mate having sliding wedging engagement beneath the plane of the rail base to grip the latter between said mate and said small jaw and an additional jaw on said yoke arranged to the rear of the other jaws.

6. A rail anchor comprising a yoke adapted to grip the rail base flanges both above and below the same, the areas of contact on the upper side of the rail base being in ad-

vance of those on the lower side, means bearing against a cross-tie to maintain said rail anchor in gripping position and additional means engaging the upper surface of the rail base to the rear of the before mentioned areas of contact to maintain said rail anchor in position independently of the pressure against said tie.

7. A rail anchor comprising a yoke which bears against the rail base both above and below the same, the portion beneath the rail being arranged to the rear of the portion above said rail and a wedge shaped member fitting within said yoke at one side of the rail base.

8. A rail anchor comprising a yoke having a jaw at each end, a wedging member received within one of said jaws in sliding engagement therewith and means at the opposite end of said yoke for engaging said rail base at a point to the rear of the corresponding jaw.

9. A rail anchor comprising a yoke having a jaw at one end which fits the rail base, a larger jaw at the other end and a portion depressed to provide a clearance beneath the rail base, a wedging member received within said larger jaw and said clearance and having wedging engagement with said yoke beneath the rail base and flexible means on said larger jaw adapted to be bent to engage said wedging member.

10. A rail anchor comprising a casting hung from a rail base and having jaws which increase their grip when said casting is tilted, one of said jaws being detachable and means for preventing accidental detachment thereof.

11. An anti-creeper comprising means arranged to engage a rail base above and below the same and having a tie engaging flange beneath the rail, the parts being so disposed as to cause a tendency of said anti-creeper to tilt about a transverse horizontal axis when the rail tends to creep, to increase the grip of the anti-creeper on said rail base and means for preventing tilting in a reverse direction.

12. A rail anchor having portions which fit against one edge of a rail base and grip the same above and below at points offset with respect to the length of the rail to resist creeping, and having a flange which extends downwardly from adjacent said edge and bears against a tie, whereby the creeping thrust tends to tilt said anchor about a horizontal axis transverse to the length of the rail, thus increasing the grip on said rail base, and means for preventing tilting in a reverse direction to prevent the rail anchor from relaxing its hold on the rail base.

13. A rail anchor having portions which fit against one edge of a rail base and grip the same above and below at points offset with

respect to the length of the rail to resist creeping, and having a flange which extends downwardly from adjacent said edge to bear against a tie, whereby the creeping thrust tends to tilt said anchor about a horizontal axis transverse to the length of the rail to increase the grip on said rail base, and an integral extension on said rail anchor having means associated therewith for engaging one of the opposite vertical faces of said rail to hold said foregoing parts in position on said rail base.

14. A rail anchor comprising an integral casting fitting over one edge of a rail base, the area of contact with the bottom of said rail base being between the front and rear extremes of the area of contact with the top of said rail base, a flange extending downwardly from adjacent the edge of the rail base and bearing against a tie, and means associated with said casting for holding the said rail anchor against the edge of said rail base.

15. A rail anchor comprising an integral member fitting over one edge of a rail base, the area of contact with the bottom of said rail base being between the front and rear extremes of the area of contact with the top of said rail base, a flange extending downwardly from adjacent the edge of the rail base and bearing against the tie, means for holding said rail anchor in position and a flexible element adapted to be bent to insure the permanent retention of said anchor by said means.

16. A rail anchor comprising a member fitting over one edge of a rail base having contact therewith above and below the same, contact on top of the rail base being made at points both in advance of and as far to the rear as contact beneath said rail base whereby tilting either backward or forward about a horizontal axis transverse to the rail base is prevented, a tie-abutting flange arranged beneath and mainly to one side of the rail base, ribs for reinforcing the latter both longitudinally and transversely, and means carried by said casting for co-operating with a vertical wall of said rail on the side opposite the before mentioned rail base edge to hold said casting in operative position, whereby the creeping thrust insures a powerful grip of the anchor on said rail base edge.

17. A rail anchor comprising a tie-abutting flange arranged adjacent to one edge of a rail base and extending both above and below the latter, transverse projections integral with said flange and fitting over said rail base both above and below, the point of contact with the bottom of said base being between the extreme forward and rear points of contact with the top of said rail base, one of said projections being extended more than the others and having means co-oper-

- ating therewith for positively engaging a vertical surface on the opposite side of the rail to insure the retention of said anchor in position.
- 5 18. A rail anchor comprising a part arranged to contact with the base of a rail, contact with the top of said rail base being somewhat extended longitudinally of said rail base, and contact with the bottom there-
10 of being much less extended longitudinally, said bottom contact taking place near the rear boundary of the upper contact, and a flange projecting downwardly to bear against the side of a tie at some distance
15 below the base of the rail.
19. In an anti-creeper, a member providing contact with the upper surface of one of the rail base flanges as well as with the lower surface thereof, and having a down-
20 wardly extending tie-abutting flange, the creeping thrust tending to tilt said anti- creeper about a horizontal axis whereby the forward area of said upper contact bears downwardly on said rail base in resisting
25 creeping, the lower contact being to the rear of said forward area and bearing upwardly against said rail base in resisting creeping, and the rear area of said upper contact being at least as far to the rear as said lower
30 contact and acting upon a tendency to tilt said member in a reverse direction to exert pressure against the top of said rail base and resist said tilting.
20. An anti-creeper comprising a casting
35 having a part which contacts with the top of a rail base flange adjacent to one side of a tie, a part which contacts with the bottom of said base flange considerably to the rear of said tie, a depending element engag-
40 ing said side of said tie beneath the edge of said base flange, whereby the creeping thrust causes said parts to grip said base flange and a part which contacts with the top of
- said base flange at least as far to the rear as said bottom contact part. 45
21. A rail anchor comprising a casting having parts projecting laterally both above and below the side of a rail base to grip the latter, the part projecting beneath the rail base being arranged near the rear of the 50 area of contact with the top of said rail base, a vertically arranged downwardly ex- tending flange at the forward termination of said top contact area and arranged mainly outside of the vertical plane of the 55 edge of the rail base and a forward exten- sion at the lower end of said flange to en- gage said tie at said lower end only.
22. A rail anchor comprising a casting having means fitting over one edge of a rail 60 base, a downwardly extending substantially vertical flange arranged transversely with respect to the length of the rail and near to the side thereof and a reinforcing rib ex- tending rearwardly from said flange and ar- 65 ranged in substantially a vertical plane ad- jacent to the rail base edge.
23. A rail anchor comprising a casting having lateral extensions fitting above and below a rail base flange, a vertical web ar- 70 ranged substantially in the plane of the edge of said base flange, a downwardly ex- tending flange arranged in a plane at right angles to said web and mainly on the side thereof away from the rail, a forward exten- 75 sion at the lower end of said flange for en- gaging a tie, and means for holding said casting in position on said base flange.

In witness whereof, I have hereunto sub-
scribed my name in the presence of two 80
witnesses.

PHILIP W. MOORE.

It is hereby certified that in Letters Patent No. 1,140,345, granted May 18, 1915, upon the application of Philip W. Moore, of Evanston, Illinois, for an improvement in "Anticreepers," an error appears in the printed specification requiring correction as follows: Page 4, line 63, strike out the word "to", second occurrence; and that the said Letters Patent should be read with this correction therein that the same may conform to the record of the case in the Patent Office.

Signed and sealed this 8th day of June, A. D., 1915.

{SEAL.}

R. F. WHITEHEAD,

Acting Commissioner of Patents.
